[57] CLAIM

The ornamental design for a combined ceiling fan and
light, as shown and described.

DESCRIPTION

FIG. 1 is a perspective of the combined ceiling fan and
light as seen from the lower side;

FIG. 2 is a side elevational view thereof, each side
elevational view being identical;

FIG. 3 is a reduced bottom plan view of the ceiling fan;
and,

FIG. 4 is a top plan view of the ceiling fan.
The support rod has been shown broken away in FIGS.
1 and 2 to indicate indeterminate length.
